UNITED STATES PATENT OFFICE.

JAMES McLAUGHLIN, OF DOLTON, ILLINOIS, ASSIGNOR TO RICHARD FITZGERALD, OF CHICAGO, ILLINOIS.

METHOD AND MEANS FOR BAKING BRICK.

Application filed January 11, 1926. Serial No. 80,627.

This invention relates to an improved method and means for baking brick.

In practice it is often desirable to bake large quantities of brick in one operation, 5 as many as a million brick being baked at one time. Suitable heat retaining means must be provided for the stack in order to insure that the green brick will be evenly and thoroughly baked. Permanent kilns 10 are unsatisfactory for this use, and this is particularly true if large quantities of brick are to be baked at one operation, owing to expense of construction, structural limitations as to size, the necessity for handling 15 the brick by hand, etc. Accordingly, it is the common practice to stack the green brick in such a manner as to provide interstices for the heating gases of combustion, and to apply a coating of refractory material, such 20 as ordinary clay, to the outer layer of the stack. The clay fills the interstices between the bricks of the outer layer, whereby the latter constitute the walls of a kiln, suitable openings being provided in the top of the 25 stack to ensure the necessary draft. Heat is then applied in a suitable manner adjacent the bottom of the stack to bake the green brick. This method of baking brick presents several difficulties. Much time and 30 labor is consumed in applying the clay to the outer bricks of the stack and after the bricks are baked, it is necessary to remove the outer coating. During the baking operation the clay adheres to or fuses with the 35 outer layer of brick and it is necessary, in order to remove the clay, to remove said outer layer. Considerable labor and expense is involved in this operation and the removed bricks are of no value as such but 40 must be ground up if the material therein is to be further employed.

Because of the many difficulties arising from the use of permanent kilns and the use of clay, it has heretofore been proposed to 45 employ various types of portable or sectional structures as heat retaining means, such structures being referred to in the art as portable scovings. The typical form of scovings used consists of a number of plates, 50 usually of metal, which are faced with heat resisting material, such as fire brick. Sections, constituted by the insulated plates, are adapted to be assembled as a kiln structure. Scovings of this type is expensive to 55 construct, and owing to the size and weight of

the sections, is difficult to handle. Machinery is required for assembling the sections and considerable time and labor is involved. Moreover, as now constructed, foundations are required for the scovings and expensive 60 and complicated means are necessary for securing the sections together.

An object of the present invention is to overcome the above difficulties by providing an improved method and means for baking 65 brick whereby all waste of brick may be avoided.

Another object is to avoid the expense involved in constructing a permanent kiln.

Another object is to provide a method 70 which may be readily and quickly carried out by unskilled labor, and without the necessity for handling machinery, such as is required by the use of the usual portable scovings. Other objects will appear more 75 fully hereinafter.

One manner in which the heat retaining covering of the present invention may be associated with a stack of brick is illustrated in the accompanying drawing, wherein a part of said covering is broken away to show the stacked brick, but it is to be expressly understood that this drawing is for purposes of illustration only and is not to be construed as a definition of the limits 80 of the invention, reference being had to the appended claims for this purpose.

Referring to the drawings, the green bricks 1 to be baked are stacked in the usual manner to provide openings or "arches" 2 90 for the reception of suitable burners (not shown), such as oil burners, and the usual interstices 3 for the passage of the heating or baking gases.

In order to retain the heat within the 95 stack during the baking operation, a suitable scovings or heat retaining covering is provided which is inexpensive, light in weight, and which may be quickly and easily applied to the brick. Preferably this scovings or covering is constituted by sheets 100 4 of non-inflammable material, and of suitable thickness and size. While the sheets may be of metal, preferably asbestos is employed. The heat retaining means need not be constituted as a preformed unitary sheeting, a plurality of sheets of various sizes being placed directly on or against the green brick 105 and supported thereby. The sheets constituting the side walls of the covering may 110

be readily attached to the green brick as by means of nails or staples 6, etc. If desired, the sheets may be of such size that the vertical portion thereof or the portion 5 employed as a side wall may be retained in place by bending the upper end of the sheets over the top of the stack, and if necessary, said sheets may be retained in place by nails driven through the latter into the green 10 brick, or portions of the edge of the sheet may be inserted in the interstices 3. It will be apparent that the covering may be constituted by a plurality of sheets which are merely placed over the stack to rest on the 15 top layer of bricks and having the opposite ends of the same bent downwardly to cover the sides of the stack.

With the stack thus prepared and covered heat is introduced through the openings 2 and 20 the gases of combustion will pass upward through the interstices between the brick and out through suitable openings provided in the top covering, if desired. The entire stack of brick thus receives an even baking. 25 When the operation is completed the covering or scoving is readily removable and may be employed again and again.

It will be apparent that there is provided a novel method and means for baking brick 30 which are inexpensive and which avoid waste. A minimum of time, labor and expense are required to apply or remove the heat retaining covering. The latter is readily attachable to stacks of varying sizes and 35 does not require the use of supporting or connecting means such as are employed in types of portable scoving now used. The plurality of sheets employed as heat retaining means may be associated in any suitable 40 manner, as by overlapping the individual sheets. They may be retained in place by their own weight or, if desired, by the use of nails or suitable props. Openings may be provided at any convenient 45 point or points by properly placing the sheets; or openings may be closed, if desired, by the use of an additional sheet or sheets.

As shown in the drawing, the stack of 50 green brick may be erected in a shed 5, since such sheds are commonly employed in brick yards and are usually provided with machinery for handling and stacking the green brick. The shed, however, constitutes no 55 part of the present invention.

It is to be expressly understood that the invention is not restricted to any particular stacking of the bricks, the number of bricks which may be baked at one time, or the number and size of sheets employed in 60 the heat retaining covering. Reference is therefore to be had to the appended claims for a definition of the limits of the invention.

I claim:

1. A method of baking brick, consisting in stacking said brick, covering said stack with a plurality of loosely associated sheets of heat-retaining material resting thereon, and subjecting said stack to the action of 70 heat.

2. A method of baking brick, consisting in stacking the green brick so as to form heat conducting passages through the stack, placing a covering comprising sheets of heat-retaining material on said stack, and passing heated gases through said passages.

3. A method of baking brick, consisting in stacking the brick, hanging a plurality of loose flexible sheets of heat-retaining material over the stack to constitute a cover therefor, and subjecting the stack to the action of heat.

4. A scoving for baking brick comprising a plurality of loosely associated sheets of heat-retaining material placed over a stack of bricks to be baked and resting thereon.

5. A scoving for baking brick comprising a plurality of sheets of asbestos, and means for attaching the sheets directly to the brick 90 to be baked.

6. A scoving for baking brick comprising sheets of non-inflammable and heat-retaining material adapted to constitute a cover for a stack of bricks to be baked when said sheets are placed thereon, said cover being entirely supported by said bricks.

7. A scoving for baking brick comprising a plurality of loose sheets of heat-retaining material, said sheets being supported by a stack of brick to be baked and constituting a cover therefor.

8. A scoving for baking brick comprising a plurality of loosely associated flexible sheets of heat-retaining material placed on a stack of brick to be baked and constituting a cover therefor.

In testimony whereof I have signed this specification.

JAMES McLAUGHLIN.
